(57) **CLAIM**

The ornamental design for a conveyor belt slat, as shown and described.

DESCRIPTION

FIG. 1 is a front view of a conveyor belt slat showing our new design;

FIG. 2 is a top view thereof;

FIG. 3 is a bottom view thereof;

FIG. 4 is a side view thereof;

FIG. 5 is an opposite side view thereof;

FIG. 6 is an upper perspective view thereof; and,

FIG. 7 is a lower perspective view thereof.
